(57) **CLAIM**

The ornamental design for a “dolphin pillow,” as shown.

DESCRIPTION

FIG. 1 is a perspective view of a dolphin pillow showing my new design;

FIG. 2 is a front view thereof;

FIG. 3 is a rear view thereof;

FIG. 4 is a side view thereof;

FIG. 5 is a top plan view thereof; and,

FIG. 6 is a bottom plan view thereof.

In the drawings, the broken lines represent stitching forming part of the claimed design.
